UNITED STATES PATENT OFFICE.

CHARLES L. PORTER, OF CHICAGO, ILLINOIS.

APPARATUS FOR RESTORING THE SPENT PROPERTIES OF CHARCOAL.

SPECIFICATION forming part of Letters Patent No. 391,335, dated October 16, 1888.

Application filed December 17, 1887. Serial No. 258,174. (No model.)

To all whom it may concern:

Be it known that I, CHARLES L. PORTER, of Chicago, county of Cook, and State of Illinois, have invented certain new and useful Improvements in Apparatus for Restoring the Spent Properties of Charcoal, of which the following is a full, clear, and exact description, that will enable others to make and use the same, reference being had to the accompanying drawings, forming a part of this specification.

The object of this invention is to provide a means for restoring animal or wood charcoal to its original condition after the same has been used in the manufacture of glycerine.

This apparatus is designed to be used in carrying out the process set forth in application No. 268,894.

The charcoal used in filtering glycerine absorbs and retains all the residue and foreign substance not wanted in the glycerine. Now by subjecting the spent charcoal to the treatment hereinafter set forth it is found that all the matter absorbed from the glycerine may be drawn out and the cleansing and purifying properties of the charcoal restored, so that it may again be used as a cleansing agent.

Figure 1 is a sectional side elevation of an apparatus employed in carrying out my improvement; and Fig. 2, a horizontal section 30 of the same in the plane 2, Fig. 1.

Referring to the drawings, A represents a cylindrical boiler-like receptacle or retort which is set similar to that of the ordinary steam-boiler; A', the masonry or walls inclosing the same; A², the combustion-chamber; A³, the grate-bars; and A⁴, the ash-pit.

B is the ordinary fire-front provided with the usual furnace and ash-pit doors, the front end of the receptacle A projecting beyond the 40 line of the same, as shown in Fig. 1.

B' is a steam-coil arranged in a horizontal position and located about midway between the grate-bars and the under side of the receptacle. This coil covers the whole width and 45 length of the furnace (see Fig. 2) and is supplied with steam through the pipe B², which connects with some convenient steam-generator. The pipe B³, leading from the opposite side of the coil, conducts the steam to the rear 50 end of the receptacle and discharges the same

into the steam-chamber a, from whence it passes into the receptacle compartment proper through the perforated diaphragm a'. The pipe B³ is provided with the stop-valve a² for opening and closing the steam-passage. A second steam-chamber, a³, is formed at the opposite end of the receptacle, the steam passing into the same through the perforated diaphragm a⁴. This diaphragm is rigidly secured to the removable receptacle-head C by means of a number of bolts, b, so that when the head is taken off the diaphragm is also removed.

b' is a steam escape or exhaust pipe.

The dome C is provided with the removable cover b².

Above the receptacle and resting on the side walls of the inclosing masonry is the platform D, provided around the edge with the combing d. This platform will ordinarily be composed of iron and will extend from wall to 70 wall. In this case the products of combustion do not pass through the receptacle, but under, and upward at the back end and then pass along underneath and heat the platform D, and finally escape through the smoke-flue D'. 75

In the process of manufacturing glycerine the charcoal, after being used in filtering the same, is subjected to a water bath for the purpose of removing a part of the residue matter absorbed. The charcoal, after being drained 80 from the water bath, is next thrown onto the platform D, and the receptacle or tank filled with the same through the dome C. A fire is then started under the receptacle and the charcoal subjected to a direct heat for the purpose 85 of expelling the extraneous moisture and foreign matter absorbed. After the charcoal in the receptacle has become heated somewhat the valve a² is opened and steam allowed to enter the receptacle. This steam, first passing through the furnace-coil B', is superheated before it enters and fills the chamber a in the back end of the receptacle, from whence the steam is forced into the mass of charcoal through the numerous perforations in the diaphragm a', which arrangement has the effect of separating the volume of steam into jets, so that the same will more uniformly penetrate and pass through the body of charcoal. Steam under a high pressure may be used without 90 95 100

being superheated; but the latter will do the work in less time and more efficiently, and for that reason is preferable. The water bath may be omitted, but it is better to use the same, as it greatly shortens the process. The steam after passing through the body of charcoal enters the chamber a^3 and escapes therefrom through the pipe b' . This heating and steaming process continues until the steam escaping from the pipe b' is found to be perfectly dry. The fire should now be extinguished and the steam shut off, the process being completed and the original properties of the charcoal restored, so that it may be again utilized. The charcoal is taken out by removing the head or boiler end C. The receptacle may then be recharged and the process repeated.

During the process of treating one charge in the receptacle a second charge may be deposited on the platform and heated to a greater or less degree, which will expedite and greatly facilitate the final process.

Having thus described my invention, what I claim as new, and desire to secure by Letters Patent, is—

In an apparatus of the character described, the combination, with a boiler-like receptacle or retort, of a combustion chamber, a superheating steam-coil located therein, a pipe connected to and supplying said coil with steam, a second pipe for conducting and discharging the superheated steam into the chamber a in the rear end of said receptacle, the perforated diaphragm a' , the chamber a^3 , located in the opposite or front end of said receptacle, the perforated diaphragm a^4 , and an escape pipe leading from the chamber a^3 , all constructed and arranged to operate substantially as and for the purpose set forth.
